CLAIM

The ornamental design for a docking station, as shown and described.

DESCRIPTION

FIG. 1 is a perspective view of a docking station showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, holding a portable electronic device.

The dashed broken line portions of the docking station represent unclaimed portions of the claimed design and form no part thereof.

The broken lines in FIG. 8, showing the additional portable electronic device, depict environment only and form no part of the claim.

1 Claim, 8 Drawing Sheets
